(57) **CLAIM**

The ornamental design for a camera having retractable attachment mechanism, as shown and described.

DESCRIPTION

FIG. 1 is a perspective view of a camera having retractable attachment mechanism showing our new design with the lens cover in an unfolded position and the attachment mechanism in an extended position;

FIG. 2 is a perspective view thereof showing our new design with the lens cover in a folded position and the attachment mechanism in a retracted position;

FIG. 3 is a front elevational view thereof with the lens cover in the unfolded position and the attachment mechanism in the extended position;

FIG. 4 is a right elevational view, the left elevational view being a mirror image thereof;

FIG. 5 is a top plan view thereof with the lens cover in the unfolded position and the attachment mechanism in the retracted position;

FIG. 6 is a front elevational view thereof with the lens cover in the folded position and the attachment mechanism in the retracted position;

FIG. 7 is a right elevational view, the left elevational view being a mirror image thereof;

FIG. 8 is a rear elevational view thereof; and,

FIG. 9 is a top plan view thereof.

Phantom lining, where utilized, is for illustrative purposes only, and is not intended to limit the claimed design to the features shown in phantom.
